194,848

DESK, OR SIMILAR ARTICLE

Angelo F. Monteverdi, Beverly Hills, Calif., assignor to Monteverdi-Young, Inc., Los Angeles, Calif., a corporation of California

Filed Apr. 30, 1962, Ser. No. 69,897

Term of patent 14 years

(Cl. D33—7)

FIG. 1.

FIG. 2.

FIG. 4.

FIG. 3.

FIG. 5.

FIG. 1 is a front perspective view of a desk or similar article showing my design;

FIG. 2 is a top plan view on a reduced scale;

FIG. 3 is a front elevational view of the desk of FIG. 2;

FIG. 4 is a left side elevational view; and

FIG. 5 is a bottom plan view thereof.

I claim:

The ornamental design for a desk, or similar article, substantially as shown.
